UNITED STATES PATENT OFFICE.

WILLIAM CLARKE S. MAYS, OF EDGEWOOD, RHODE ISLAND, ASSIGNOR TO MAYS MANUFACTURING COMPANY, INC., OF PROVIDENCE, RHODE ISLAND, A CORPORATION OF RHODE ISLAND.

FASTENER.

Application filed July 25, 1925. Serial No. 46,010.

To all whom it may concern:

Be it known that I, WILLIAM CLARKE S. MAYS, a citizen of the United States, residing at Edgewood, in the county of Providence and State of Rhode Island, have invented certain new and useful Improvements in Fasteners, of which the following is a specification.

This invention relates to bendable garment-fasteners of the class adapted more particularly to be used in laundries as a temporary fastener for soft cuffs, or the like, of freshly laundered shirts and other articles of clothing; and this invention has for its object to form such a fastener of a thin strip of radially bendable metal having arms concavo-convex in cross section to stiffen the same and an intermediate bridge portion not so stiffened and more responsive to bending than either of said concavo-convex arm portions.

A further object of the invention is to provide a fastener with arm portions arranged at an angle to the connecting bridge portion so that the fastener will not lie flat on a table but will rather have one portion raised to permit it to be readily grasped and picked up by the fingers.

A further object of the invention is to dispose the arm portions at an angle to the bridge portion and to provide a partially bent connecting portion to assist in determining the point of bending between the arms and bridge portions.

With these and other objects in view, the invention consists of certain novel features of construction, as will be more fully described, and particularly pointed out in the appended claims.

40 In the accompanying drawings:

Figure 1 is a perspective view of a freshly-laundered soft-shirt cuff showing my fastener as applied to the same.

Figure 2 is a plan view of a fastener.

45 Figure 3 is a perspective view of the same showing the concavo-convex arms.

Figure 4 is a side elevation of the fastener.

50 Figure 5 is a central sectional elevation of the same.

Figure 6 is a section on line 6—6 of Figure 2.

Figure 7 is a section through the concavo-convex arm, taken on line 7—7 of Figure 2.

Figure 8 is a perspective view showing 55 the fastener bent to the position that it will assume after having been placed through a buttonhole in a soft-shirt cuff or the like.

It is found by laundries desirable to 60 secure the cuffs and collar bands of soft shirts together by a bendable metal member which is stiffened for a portion of its length and also provide with portions of less stiffness to determine the points of bending of 65 the metal when placed through the buttonholes of multiple layers of soft fabrics, such as cuffs or the like, and it is also desirable that the fastener should be of thin material and of such construction as 70 to lie closely and flat against the outer surfaces of the fabric to which it is attached; and the following is a detailed description of one construction of fastener by 75 which these advantageous results may be obtained.

With reference to the drawing, 10 designates a strip of metal of the desired length, which is preferably formed very thin and of ductile, soft and bendable material, the 80 same being adapted to pass through the buttonholes 11 of a freshly laundered shirt cuff 12, for the purpose of holding the layers of fabric in the desired finished position. It is also found of advantage to so form this 85 fastener that it will have a middle or bridge portion 13 to space the arm portions 14 so that the same will lie substantially parallel and close to the opposite outer surfaces of layers of fabric, the ends of the arm portions 14 being bent against the outer surfaces of the fabric to bind the fastener permanently in position.

In order to determine the point of bending between the arm and bridge portions, I 95 have stiffened the arm portions 14 by making them concavo-convex in cross section, as shown in Figure 7, whereas the bridge portion is not so stiffened and lies substantially in a single plane as shown in 100

Figure 6, and in order to assist in determining the point of bending between the arm and bridge portion, I have set the bridge portion 13 in a different plane from that of the arm portion 14 to provide a partially bent portion 15, as clearly shown in Figures 4 and 5, whereby when folding-pressure is applied to the ends of the arm portion, the strip naturally bends along the lines of the 10 partially bent portion 15 of the unstiffened connecting portion between the bridge and arms.

I also position the arm portions 14 at an angle to the bridge portion 13 whereby the 15 fastener in resting upon a table or other flat surface will always have one portion raised, as clearly shown in Figure 3, so that the same may be readily picked up by the fingers, to be used. In use, one end of the 20 fastener is placed through a buttonhole in the fabric and then by drawing the thumb and finger endways with a wiping or stripping motion, the arms or ends of the strip are readily bent down and caused to lie 25 against the opposite faces of the fabric.

It will be noticed that the above description is directed to a fastener which is extremely simple in construction and yet is practical in its operation.

30 The foregoing description is directed solely towards the construction illustrated, but I desire it to be understood that I reserve the privilege of resorting to all the mechanical changes to which the device is

susceptible, the invention being defined and limited only by the terms of the appended claims.

I claim:

1. A cuff fastener formed of a thin strip of bendable metal having a bridge portion lying in substantially a single plane, longitudinally extending arms arranged at an angle to said bridge portion, said bridge portion being bent or offset sharply from said arms and weakened at the bend rendering further bending of the arms where they connect the bridge portion more responsive to bending pressure than either said arms or bridge portion.

40 2. A cuff fastener formed of a thin strip of bendable metal of substantially uniform width and having longitudinally disposed arm portions concavo-convex in cross section on substantially the same arc of a circle through their length and spaced apart by an intermediate portion more responsive to bending than either of said arm portions.

45 3. A cuff fastener formed of a thin strip of bendable metal having a bridge portion lying in substantially a single plane, longitudinally extending arms concavo-convex in cross section throughout their length arranged at an angle to said bridge portion, and a portion connecting said bridge portion and arms more responsive to bending than either said bridge portion or arms.

50 In testimony whereof I affix my signature.

WILLIAM CLARKE S. MAYS.
